CLAIM

We claim the ornamental design for a plug-in night light, as shown and described.

DESCRIPTION

FIG. 1 is a front view for a plug-in night light;
FIG. 2 is a right side view thereof;
FIG. 3 is a left side view thereof;
FIG. 4 is a top view thereof;
FIG. 5 is a bottom view thereof;
FIG. 6 is a back view thereof; and,
FIG. 7 is a front perspective view thereof.
The broken lines in the figures depict portions of the article which form no part of the claimed design.
